TYPOGRAPHICAL CASTING MACHINE

Anthony Joseph Stouges, Queens Village, N. Y.,
assignor to Mergenthaler Linotype Company, a
corporation of New York

Application September 24, 1932, Serial No. 634,646

48 Claims. (Cl. 199—54)

This invention relates to typographical casting machines, such as linotype machines of the general organization represented in U. S. Letters Patent to O. Mergenthaler No. 436,532, wherein a melting pot is arranged to deliver molten metal into a slotted mold and up against a composed line of matrices to produce a type bar or slug bearing on its edge type characters corresponding to the intaglio characters of the matrices. In 10 these machines, the molds (usually four in number) are mounted in a rotatable wheel or disc which may be adjusted to bring any selected mold into use. During each machine cycle of operation, the active mold, by successive partial rotations of the disc, is first presented in a horizontal position for casting of the slug and thereafter presented in a vertical position for ejection of the slug.

In casting slugs, especially the larger slugs, say 20 from 42 pt. to 144 pt., high spots frequently occur in the printing faces of the slugs and, unless removed, cause corresponding imperfections in the printed matter. Such imperfections are due largely to slight irregularities or unevenness in 25 the bottom surface of the matrix cavities or characters and, although extreme care and accuracy are observed in the course of matrix manufacture, the degree of perfection attained in punching or forming the characters is governed more or less 30 by variations in the grain of the metal used and is, therefore, very uncertain. In overcoming the above difficulty, it has heretofore been the common practice to rub the printing faces of slugs upon an emery coated block before assemblage 35 in the printing forms. This practice, however, requires that each slug be handled and inspected separately, and is slow, tedious, and otherwise objectionable.

The present invention aims to dispense entirely 40 with all such manual operations, and contemplates means for automatically finishing the printing faces of the slugs while they are still in the mold. To this end, specifically, the machine is equipped with a high speed power driven rotary face cutter mounted on a fixed bracket at the front of the machine in position to act upon 45 the printing faces of the slugs as the latter are carried by the rotation of the mold disc from casting to ejecting position. The cutter is preferably driven by an electric motor and is mounted 50 so as to be automatically movable into and out of slug trimming position as the electric motor is started and stopped, respectively. The trimmed slugs not only present an even and 55 level printing face, but, in addition, a superior

printing face because of the trimming operation which hardens the type characters and eliminates the porosity so common in the past.

In the accompanying drawings, the invention is shown merely in preferred form by way of example and as applied to a commercial linotype machine, but obviously many changes and variations may be made therein and in its mode of adaptation, which will still be comprised within its spirit. It should, therefore, be understood that the invention is not limited to any specific form or embodiment, except insofar as such limitations are specified in the appended claims.

Referring to the drawings:

Fig. 1 is a front elevation of a portion of a linotype machine embodying the present improvements;

Fig. 2 is a side elevation (looking from the left) of the parts shown in Fig. 1;

Fig. 3 is a vertical view showing the internal construction of the improved cutter unit;

Fig. 4 is a front elevation of the cutter unit, partly in section, taken on line 4—4 of Fig. 3 looking in the direction of the arrows;

Fig. 5 is a top plan view of the parts shown in Fig. 1;

Fig. 6 is a top plan view, partly in section, showing the disposition of the cutter relative to the front face of the mold;

Fig. 7 is a rear elevation taken on the line 7—7 of Fig. 3 looking in the direction of the arrows, and showing the housing in which the cutter is enclosed;

Fig. 8 is a side elevation of the cutter unit taken on the line 8—8 of Fig. 1;

Fig. 9 is an elevational view of a section of the cutter; and

Fig. 10 is a vertical section through the cutter taken on the line 10—10 of Fig. 9.

After the composed line of matrices has been delivered to the vertically movable line transporter or first elevator and presented thereby in front of the slotted mold (such as the mold *a*) carried by the rotatable wheel or mold disc *A*, the disc is advanced bodily from the rear to carry the aligning rib of the active mold into engaging relation with the lower projecting ears of the matrices preparatory to the justification of the line and the alignment of the matrix characters with the mold slot. At this time the front face of the mold is out of contact with the matrix line although closely spaced therefrom (about 1/64"), the final "lock-up" or sealing of the mold slot by the matrices being subsequently effected by the 105 matrices being subsequently effected by the 110

forward movement of the metal pot. This latter operation, which takes place under powerful spring tension, forces the mouthpiece of the metal pot against the back of the mold and moves the disc A and its supporting slide C, independently of their controlling mechanism, forwardly to close the small gap between the matrix line and the face of the mold.

Molten metal is then forced into the mold by one or more spring actuated metal pot plungers, and after the slug is cast the mold slide C is retracted to carry the mold out of contact with the line and the disc A then given a three-quarter turn in an anti-clockwise direction to carry the slug from the horizontal casting to the vertical ejecting position. During such rotation of the disc A, the active mold is swept past a stationary back knife which is arranged behind the disc and adapted to trim off any burrs or surplus type metal that may adhere to the rear edge of the slug.

So far as described, the parts, their construction, and mode of operation, except as hereinafter pointed out, are or may be the same as those embodied in the commercial linotype machine and in themselves constitute no part of the present invention.

The several molds *a* (usually four) are mounted on the mold disc A and secured in place by means of clamping screws *a'* in the well-known manner. The rear faces of all of the molds are flush with the rear face of the disc A in order that the slugs produced in each may be properly trimmed by the rear knife in the manner above mentioned. In the present instance, however, any one or all of the molds may be made somewhat deeper than the regular molds ordinarily used to produce slugs of normal type height, thus providing a small excess of metal on the type characters to be trimmed off in obtaining the flawless printing faces desired.

This proposed change in the form of the molds *a* carried by the disc A will not affect other parts of the machine in the normal operation thereof, since the difference in height of the deeper molds is but .002" and, therefore, well within the 1/64" clearance space allowed between the face of the mold and the matrix line during justification and alignment. In other words, when the mold disc A is advanced for the casting operation and one of the deeper molds is in use, the front face of said mold will stand slightly closer to the matrix line than would the corresponding face of a normal depth mold at such time. Clearance will still be abundant for the required relative movement between the matrices and mold during the justifying and aligning operations. Furthermore, the slight difference in the extent of forward movement of the disc A due to the difference in depth of the molds, and which is limited by the matrix line, is compensated for by the resiliency of the pot spring when the mouth of the pot is pushed against the back of the mold.

As a result of the increased depth of the molds, the front faces of the type characters on the slugs cast therein will be disposed slightly forward of the faces of type characters on the slugs cast in the normal depth or standard type high molds when the mold disc A is backed away from the matrix line preparatory to its rotation to carry the slug from casting to ejecting position. Consequently, in casting the slugs in either a regular or a deep mold the regular linotype matrices may be used, notwithstanding the fact that the intaglio cavities or characters of said matrices, irrespective of body size or font, are of uniform depth.

As before stated, the present invention provides means for dressing down or trimming the printing faces of the cast slugs, said means in the embodiment illustrated consisting of a rotary cutter unit B mounted on a suitable bracket (see Figs. 80 1 and 2) and arranged directly opposite the rear trimming knife, the latter being located as usual on the lateral arm or extension C¹ of the mold slide C. The bracket just referred to is secured by a pair of screw bolts *b* to the extension C¹ and is formed of two members, a fore-and-aft vertical side member B¹, and an L-shaped member presenting a vertical portion B² and a laterally offset bottom flat-top member B³ (Figs. 1, 3 and 4), whereon the cutter unit B is supported in the desired position.

The cutter unit B comprises a box or housing B⁴ seated on the bracket member B³ and provided at its forward end with a bent-up bearing member B⁵ spaced slightly from the main portion of the housing. Within the housing B⁴, there is located a loosely fitted sleeve B⁶, which in turn houses a rotatable spindle B⁷ with its three supporting ball bearings. At its rear end, the spindle B⁷ is provided with a detachable face cutter B¹¹, 100 and adjacent its forward end (between the main portion of the housing B⁴ and the upturned bearing portion B⁵), it is equipped with a pulley wheel B¹² over which is passed an endless belt D running from a pulley D¹ of an electric motor D². 105

As a convenient form of detachable mounting for the cutter B¹¹, it is formed with a central threaded opening B²⁴ which can be screwed onto the rear threaded end B²³ of the spindle B⁷, the threads preferably extending in a direction opposite to the rotation of the cutter. In order to tighten the cutter B¹¹ on the spindle B⁷, the former is provided with a number of recesses B²⁵ into which prongs of a specially constructed wrench may be fitted. As will be noted in Figs. 110 9 and 10, cutting teeth B³⁰ are disposed radially on the periphery of the cutter, being flush with the forward face B³¹ of the cutter and extending beyond the rear face B³² thereof. At the rear, the projecting teeth B³⁰ are formed with bevelled cutting edges B³³, these edges being inclined in a radial direction with reference to the plane of the cutter disc, for a reason hereinafter pointed out.

The cutter spindle B⁷, which tapers from rear 125 to front, is provided near its rear end with a double row ball bearing B⁸ (of the combined radial and thrust variety); about midway of its length with a single row radial ball bearing B⁹, and near its forward end with another single row radial ball bearing B¹⁰; all of which ball bearings are fitted over the spindle from front to rear in proper order and forced onto their respective seats b⁸, b⁹, and b¹⁰. The spindle B⁷ is held in place within the sleeve B⁶ by end plates B¹³ and B¹⁴ detachably 130 secured to the sleeve B⁶, as by screws B¹⁵, both end plates having inwardly projecting flanges B¹⁶ which bear against the outer side faces of the contiguous ball bearings. The double row bearing B⁸ is held in position by a wide cylindrical thrust washer B¹⁷ abutting at one end against the inner face of the bearing B⁸ and at the other end against an annular flange B¹⁸ formed on the inner wall of the sleeve B⁶. The bearing B⁹ is maintained in its position by a spacing bushing B¹⁹ 135 closely surrounding the spindle B⁷ and spanning the space between the bearings B⁸ and B⁹. Also located between these two bearings is a cylindrical felt gasket B²⁰, forming a lubrication chamber, which incidentally is sealed at the opposite ends 140

of the sleeve B^6 by ring gaskets b^{13} and b^{14} cooperating with the end plates B^{13} and B^{14} . The third bearing B^{10} is located in the upturned end-piece B^5 , being clamped against the hub of the 5 pulley wheel B^{12} by a nut B^{21} screwed on the threaded end B^{22} of the spindle B^7 . As thus mounted the cutter spindle B^7 , aside from being 10 easily assembled, is firmly supported against side or end play, is well lubricated, and yet has its bearings 15 completely protected against the entrance of metal chips or other foreign substances.

After the sleeve B^6 with its contained parts has been placed within the housing B^4 (as can be done by entering it from the rear), it is held in 15 place therein by a sturdy stud B^{26} , the inner end of which engages in a groove or keyway B^{27} (see Fig. 5) spirally formed in the outer wall of the sleeve B^6 . As best shown in Fig. 4, the sleeve B^6 is formed near its forward end with a number of 20 threaded recesses B^{28} , into any one of which may be screwed the threaded end of a stud D^{11} which carries an operating knob or handle D^9 . The stud D^{11} is arranged in an elongated slot B^{29} cut through 25 the upper wall of the housing B^4 and hence is capable of turning the sleeve B^6 (and therefore the whole cutter unit) relatively to the fixed stud B^{26} , causing the latter by virtue of its engagement in the spiral groove B^{27} to move the cutter unit rearwardly and forwardly into or out of operative 30 position, respectively. In order to maintain the cutter in its operative position, there is provided a thumb screw D^{12} passing through a threaded recess in a raised boss B^{62} of the housing B^4 and adapted to be set up so that its inner end engages 35 with the stud D^{11} . The set screw D^{12} is angularly disposed within the boss B^{62} as shown in the drawings, so that when set up into engagement with the stud D^{11} it will tend to force the latter to the right, thus insuring both the full movement 40 of the cutter into operative position and its maintenance in said position.

The electric motor D^2 is supported on a bracket D^3 rigidly secured to the main frame E , as by screw bolts D^4 , see Fig. 2. The operation of the motor D^2 is controlled by an electric switch D^5 mounted on a bracket D^6 suspended from the bracket B' before mentioned, as by a bolt D^7 , and the switch D^5 is operated by a link D^8 pivoted at its upper end to a collar D^{10} rotatably 50 mounted on a reduced portion of the stud D^{11} above mentioned. As a result of this arrangement, when the stud D^{11} is shifted to the right (as in Fig. 4) to move the cutter unit rearwardly into operative position, it will turn on the switch D^5 to start the operation of the motor D^2 , whereas when the stud is shifted to the left to move the cutter unit forwardly into inoperative 55 position, it will turn the switch off to stop the operation of the motor. There is further provided by this arrangement a safeguard against carelessly moving the cutter into operative position and failing to put it in operation, which would be possible if two separate acts were required for moving the cutter rearwardly and for operating the switch D^5 to start the motor D^2 ; to operate the machine to deliver a slug to the cutter for trimming without the latter being in operation would render the slug useless and would injure the cutter.

In order to support and guide the mold disc A in its rotation, the supporting bracket B' is provided with a front guide or wear shoe F and a rear guide or wear shoe F' , the former being preferably formed integral with the bracket B' (see Fig. 8). The rear shoe F' , which is T-shaped

as illustrated, is formed in its body portion with a slot f through which a clamping screw f' is adapted to pass and bears against a pair of set screws f^2 and f^3 , passing through the bracket B' and having their forward ends abutting 80 against cross arms of the shoe. By first loosening and later tightening the clamping screw f' , the guide shoe F' may be adjusted by altering the setting of the screws f^2 and f^3 so as to obtain the desired evenness of pressure of the shoe 85 against the mold disc.

At its rear end, the housing B^4 is provided with a guard in the form of a rearwardly projecting hood or flange B^{50} (see Figs. 3 and 7). This guard flange practically surrounds the cutter B^{11} , but instead of being of completely circular form, it is fashioned to form a throat B^{51} leading from the cutter B^{11} to a delivery chute B^{52} (see Figs. 1 and 8) which is adapted to be attached to the housing as by bolts passing 90 through holes B^{53} . Thus, the chips and shavings removed from the slugs by the cutter B^{11} are confined by the guard B^{50} and carried off to a suitable collecting receptacle by the chute B^{52} , rather than being allowed to fall freely to 100 the floor or to be thrown off into the working parts of the machine by the rapidly rotating cutter B^{11} . Besides, the guard in conjunction with the housing and mold disc forms an enclosing chamber for the rotary cutter as a means 105 of protection to the operator.

Further to prevent the trimmings from flying upwardly and to keep the front face of the mold clean, a brush B^{54} (Fig. 6) is provided having a backing B^{55} by means of which it is secured, as 110 by bolts B^{56} , to a flange B^{57} formed integrally with the top of the guard B^{50} . The brush B^{54} is formed with yieldable bristles and in practice the wiping ends of the bristles are cut to coincide with the particular configuration of the 115 front face of the mold, as indicated at B^{58} in Fig. 6.

Having described the parts and construction of the cutter unit B , there remains to be considered its particular mounting and adjusting means. 120 At the bottom of the housing B^4 , there is provided a recess B^{35} , having a screw threaded inner portion B^{36} and a counterbored outer portion B^{37} , in which there is adapted to be secured a stud B^{38} such as that illustrated in Fig. 125 3. The stud B^{38} is adapted to fit rotatably in a recess B^{39} formed in the bracket member B^3 , the threaded portion B^{40} of the stud projecting through the bracket and adapted to receive a nut B^{41} as shown. A similar stud connection B^{42} 130 (see Figs. 1, 2, 4 and 5) is provided at the side of the cutter unit B , this connection, however, being between the bracket members B' and B^2 , B^3 , with one end of the stud secured in a threaded recess formed in the bracket member B^2 , 135 and the other end of the stud projecting through a recess formed in the bracket member B' and having a nut screwed on its projecting threaded end. These two stud connections B^{38} and B^{42} provide two pivotal mountings for the cutter 140 unit B , which, when the nuts are loosened, permit the unit to be rocked in horizontal and vertical planes.

In conjunction with the two pivotal mountings just described, there are provided two pairs 145 of set screws B^{43} and B^{44} . In adjusting the cutter unit B , the nut B^{41} and the corresponding nut of the stud connection B^{42} are loosened. By tightening one and loosening the other of the adjusting screws B^{43} , the cutter unit may be 150

rocked in a vertical plane about the pivoted connection B^{42} , either up or down, depending upon which of the adjusting screws is set up and which is unscrewed. By changing the setting 5 of the screws B^{44} , the unit may be rocked in like manner in a horizontal plane about the stud B^{38} . These adjustments permit the proper alignment of the cutter B^{11} with the front face 10 of the mold, and when such alignment has been established the nut B^{41} and that of the stud connection B^{42} are again tightened to maintain the cutter unit in its adjusted position. Of course, 15 these adjustments may be made separately; i. e., if only a horizontal adjustment is required, the nut B^{41} alone is loosened and the setting of the screws B^{43} changed, or if only the vertical adjustment is to be altered, the nut on the connection B^{42} alone is loosened and the setting of the screws B^{44} changed.

20 It may be noted at this time that the cutter unit is adjusted so that the rotary cutter B^{11} is angularly disposed with relation to the front face of the mold, (or the printing face of the slug carried by the mold and which is to be trimmed by the cutter), so that the teeth B^{30} of the cutter will engage the face of the slug only when they are at the top of the cutter during its rotation. This is well illustrated in Fig. 3, where it will be observed that the upper teeth at the point X 25 are in position to act upon the printing characters formed on the slug, whereas the lower teeth at the point Y are spaced some distance from the characters. The angular disposition of the cutter with respect to the printing face of the slug is 30 desirable to eliminate the drag which would result from engagement of the teeth at more than one point with the printing face of the slug as the latter is carried through the zone defined by the rotary cutter. And it is because of this desired 35 angular disposition of the cutter B^{11} that the teeth B^{30} thereof are formed with their radially inclined cutting edges as before described, the degree of inclination being such that when the cutter is properly aligned with the printing face 40 of the slug to be trimmed the cutting edges B^{33} , when brought into the cutting zone at the top, will be parallel to the face of the slug and hence engage therewith throughout their radial extent.

45 As before stated, the sleeve B^6 is provided with a number of screw threaded recesses B^{28} into any one of which the threaded end of the stud D^{11} of the handle D^9 is adapted to be screwed, whereby a connection between the sleeve B^6 and the electric switch D^5 is made for the purposes already indicated. By providing a number of recesses B^{28} , the initial operative (and incidentally inoperative) position of the cutter may be varied 50 to suit different conditions, as for example when casting slugs of different height. This is a very rough adjustment, however, since it is to be borne in mind that only .002" of metal or so is removed from the face of the slug, so that to effect a fine adjustment of the cutter, there is provided a micrometer screw B^{61} passing through a threaded 55 recess in the boss B^{62} of the housing B^4 , and having its inner end in engagement with the stud D^{11} . The head B^{63} of the screw B^{61} is calibrated and a pointer B^{64} secured to the boss B^{62} is provided to facilitate the reading of the calibrations 60 in determining the amount of change in the position of the cutter effected by a change in the setting of the adjusting screw B^{61} . Further, this micrometer adjustment enables the setting of the cutter in proper operative position as the teeth 65 become worn from use and from being ground 70

away in sharpening. By screwing up or unscrewing the adjusting screw B^{61} , the stud D^{11} is moved to the left (in Fig. 4) or permitted to be moved further to the right, which movements cause the sleeve B^6 to be rotated and bring about a change 80 in its fore-and-aft position. The slight changes in position of the stud D^{11} effected by the micrometer adjustment, however, are not sufficiently great to have any material effect on the electric switch D^5 .

85 The operation of the device will now be briefly described. With the cutter unit B properly adjusted so that the cutter B^{11} is angularly disposed with respect to the front face of the mold, the electric motor D^2 is started by moving the handle D^9 to the right (in Fig. 1). This movement of the handle D^9 not only turns on the switch D^5 to start the motor D^2 , but at the same time rotates the sleeve B^6 , which, because of the stud B^{26} riding in the spiral keyway B^{27} , moves the entire cutter unit rearwardly to locate the cutter B^{11} in operative position, it being maintained in this position by setting up the thumb screw D^{12} into engagement with the stud D^{11} . After the slug is cast, the mold disc A makes a three-quarter rotation to carry the slug into ejecting position, and during the first part of this rotation of the mold disc, the slug is carried past the cutter B^{11} . Because the normal rotation of the disc A is so rapid, only a fraction of a second is allowed 100 for the slug trimming operation, and for this reason a very high speed motor is employed to rotate the cutter B^{11} rapidly enough properly to dress the slug and produce a well finished printing surface. Moreover, it has been found that by the 105 employment of a "face" cutter, which cuts crosswise of the slug or transversely of the longitudinal axis of the slug, an exceptionally smooth finish may be obtained.

110 The cutter could of course be constantly driven and installed in a permanent operative position, as when used solely for trimming large slugs for head letter and display work. However, the present device is also intended for application to the regular linotype machine to be used for trimming 115 slugs of any size, so that it is a distinct advantage to be able to render the device operative or inoperative at will, and a further advantage of course to have the cutter at rest when not in use.

120 While the invention has herein been disclosed as applied to machines for producing printing slugs of standard type height, it will be understood that it is equally applicable to machines for producing printing slugs of less than standard type height, as, for example, "low" slugs which 125 when in use are supported upon blocks or fillers which position them at type height. The invention aims to cast slugs (whatever their kind) of slightly more than a given height so that when the printing faces are trimmed or dressed down the finished slug will be of the required height. This latter statement does not mean that the slugs to be trimmed must be cast of more than 130 standard type height, since the improved cutter unit can of course be set to act upon the printing faces of slugs cast type high, it being possible in 135 making up the printing form to compensate for the thickness of metal removed by the cutter.

140 Having thus described my invention, what I claim is:

1. In a typographical casting machine, the combination of a slug casting mold, and a power driven rotary cutter for automatically trimming the printing faces of slugs cast in said mold.
2. In a typographical casting machine, the

- combination of a slug casting mold movable from casting to ejecting position, and a power driven rotary cutter arranged to act upon the printing faces of slugs cast in said mold as the latter moves from casting to ejecting position. 5 80
3. In a typographical casting machine, the combination of a slug casting mold, and a power driven rotary face cutter for automatically trimming the printing faces of slugs cast in said mold. 10 85
- 10 4. In a typographical casting machine, the combination of a slug casting mold, and a power driven rotary face cutter for automatically trimming the printing faces of slugs cast in said mold, said cutter being so disposed that its cutting teeth 15 will act upon the slugs at one point only in the periphery of the cutter. 90
5. In a typographical casting machine, the combination of a slug casting mold, and a power driven rotary face cutter for automatically trimming the printing faces of slugs cast in said mold, said cutter rotating in a plane inclined with respect to the front face of the mold, but having its cutting teeth when active disposed parallel to said mold face, for the purpose described. 95
- 20 6. In a typographical casting machine, the combination of a slug casting mold movable from casting to ejecting position, and a power driven rotary cutter arranged to act upon the printing faces of slugs cast in said mold as the latter moves 25 from casting to ejecting position, said cutter being adjustable toward and away from the mold to vary its effective slug trimming position. 100
7. In a typographical casting machine, the combination of a slug casting mold, a power driven rotary cutter arranged to act upon the printing faces of slugs cast in the mold, means for moving said cutter into operative position, and means for maintaining said cutter in operative position. 105
- 30 8. In a typographical casting machine, the combination of a slug casting mold movable from casting to ejecting position, and a power driven rotary cutter arranged to act upon the printing faces of slugs cast in said mold as the latter moves 35 from casting to ejecting position, said cutter being movable at will into and out of slug trimming position. 110
9. In a typographical casting machine, the combination of a slug casting mold movable from casting to ejecting position, and a power driven rotary cutter arranged to act upon the printing faces of slugs cast in said mold as the latter moves from casting to ejecting position, said cutter being adjustable toward and away from the 40 mold to vary its effective slug trimming position, and being movable at will into and out of said slug trimming position. 115
10. In a typographical casting machine, the combination of a slug casting mold movable from casting to ejecting position, and a power driven rotary cutter arranged to act upon the printing faces of slugs cast in said mold as the latter moves from casting to ejecting position, and means providing a chamber in which the rotary cutter is enclosed. 45 120
11. In a typographical casting machine, the combination of a slug casting mold movable from casting to ejecting position, a power driven rotary cutter arranged to act upon the printing faces of slugs cast in said mold as the latter moves from casting to ejecting position, means providing a chamber in which the rotary cutter is enclosed, and a chute leading from the enclosing chamber to carry off the slug trimmings as they are 50 trapped by the chamber. 125
12. In a typographical casting machine, the combination of a slug casting mold, a periodically rotatable disc carrying said mold, a rotary dressing device arranged to act upon the printing faces of slugs cast in said mold during the normal rotation of the disc, means for actuating the dressing device, and common means for inaugurating the actuation of the dressing device and moving the same into operative position. 130
13. In a typographical casting machine, the combination of a slug casting mold, a periodically rotatable disc carrying said mold, a rotary dressing device arranged to act upon the printing faces of slugs cast in said mold during the normal rotation of the disc, means for actuating the dressing device, and common means for stopping the actuation of the dressing device and moving the same to inoperative position. 135
14. In a typographical casting machine, the combination of a slug casting mold, a periodically rotatable disc carrying said mold, a cutter arranged to trim the printing faces of slugs cast in said mold during the normal rotation of the disc, and means for moving said cutter into and out of operative position. 140
15. In a typographical casting machine, the combination of a slug casting mold, a periodically rotatable disc carrying said mold, a rotary cutter arranged to trim the printing faces of slugs cast in said mold during the normal rotation of the disc, means for actuating the cutter, and means for moving the cutter into and out of operative position. 145
16. In a typographical casting machine, the combination of a slug casting mold, a periodically rotatable disc carrying said mold, a rotary dressing device arranged to act upon the printing faces of slugs cast in said mold during the normal rotation of the disc, means for rotating said dressing device, means for rendering said rotating means inoperative, and means for automatically moving said dressing device out of operative position when its rotating means is rendered inoperative. 150
17. In a typographical casting machine, the combination of a slug casting mold, a periodically rotatable disc carrying said mold, a rotary dressing device arranged to act upon the printing faces of slugs cast in said mold during the normal rotation of the disc, means for rotating said dressing device, means for rendering said rotating means operative, and means for automatically moving said dressing device into operative position when its rotating means is rendered operative. 150
18. In a typographical casting machine, the combination of a slug casting mold, a periodically rotatable disc carrying said mold, a rotary dressing device arranged to act upon the printing faces of slugs cast in said mold during the normal rotation of the disc, means for rotating said dressing device, means for rendering said rotating means operative and inoperative, and means for automatically moving said dressing device into and out of operative position as its rotating means is rendered operative and inoperative, respectively. 150
19. In a typographical casting machine, the combination of a slug casting mold, a periodically rotatable disc carrying said mold, a rotatable dressing device arranged to act upon the printing faces of slugs cast in said mold during the normal rotation of the disc, an electric motor for rotating said dressing device, a switch for turning the motor on and off, and common means 150

for operating the switch and for moving the dressing device into and out of slug dressing position.

20. A combination as set forth in claim 3, characterized by the fact that the cutter is slidably supported at the front of the mold disc for fore-and-aft movement, whereby it may be moved into and out of slug trimming position.

21. A combination as set forth in claim 3, including means providing for vertical and horizontal adjustment of the cutter to align the same with the face of the mold.

22. A combination as set forth in claim 3, including means providing for a fore-and-aft adjustment of the cutter, whereby its slug trimming position may be varied as required.

23. A combination as set forth in claim 3, characterized by the fact that the rotary cutter is provided with radially disposed cutting teeth, the cutting edges of which are radially inclined, and the cutter is adapted to be angularly disposed with relation to the front face of the mold.

24. A combination as set forth in claim 2, including means for catching the slug trimmings produced by the cutter.

25. A combination as set forth in claim 2, including a guard surrounding the cutter and to the lower end of which is attached a chute for carrying off the slug trimmings.

26. A combination as set forth in claim 2, including means for removing slug trimmings produced by the cutter from the face of the mold.

27. A combination as set forth in claim 2, including a wiper of flexible material overlying the cutter and adapted to contact the front face of the mold, whereby slug trimmings produced by the cutter are prevented from flying upwardly and trimmings which cling to the front face of the mold are removed.

28. In a typographical casting machine, the combination of a slug casting mold, a rotatable disc wherein the mold is mounted, a back knife for trimming the bases of slugs cast in the mold, a rotary knife for trimming the printing faces of said slugs, and guide means common to both knives for restraining the disc against facewise displacement in either direction during the slug trimming operations.

29. In a typographical casting machine, the combination of a slug casting mold, a rotatable disc wherein the mold is mounted, a back knife for trimming the bases of slugs cast in the mold, a rotary cutter for trimming the printing faces of said slugs, and front and rear wear shoes for restraining the disc against facewise displacement in either direction during the slug trimming operations, at least one of said wear shoes being adjustable to even up the pressure on the mold disc.

30. In a typographical casting machine, the combination of a slug casting mold, a disc carrying said mold, a rotary cutter for trimming the printing faces of said slugs, a slide on which the mold disc is rotatably mounted, and a bracket fastened to said slide and whereon the cutter is mounted.

31. A combination as in claim 30, including front and rear wear shoes carried by the bracket for restraining the disc against facewise displacement in either direction during the slug trimming operations.

32. A combination as in claim 30, including front and rear wear shoes for restraining the disc against facewise displacement in either direction during the slug trimming operations, the front wear shoe being formed integrally with the

cutter supporting bracket and the rear wear shoe being adjustably mounted on said bracket.

33. In or for a slug casting machine, the combination of a slug casting mold, a disc carrying said mold, a slide on which the mold disc is rotatably mounted, a rotary dressing device for acting upon the printing faces of slugs cast in said mold, and a bracket whereon the rotary dressing device is mounted, said bracket being formed in two sections, one of which sections is fixedly attached to the mold disc slide, and the other of said sections being adjustably secured to said fixed section. 80

34. In or for a slug casting machine, a dressing unit for finishing the printing faces of slugs, said unit including a housing, a sleeve mounted in said housing, a spindle supported in the sleeve, a rotary dressing device secured to one end of said spindle, and a driving pulley secured to the opposite end of said spindle, said spindle being mounted in ball bearings to prevent side and end play and to eliminate chattering during rotation of the spindle. 90

35. A slug dressing unit as set forth in claim 34, wherein the housing is rigidly supported by a fixed bracket and the sleeve is movable within the housing to effect a fore-and-aft movement of the spindle, whereby the dressing device may be moved toward or away from the front face of the mold. 100

36. A slug dressing unit as set forth in claim 34, wherein the housing is pivotally mounted on a fixed bracket, whereby the entire dressing device unit may be rocked vertically or horizontally to align the dressing device with the face of the mold. 105

37. A slug dressing unit as set forth in claim 34, wherein means is provided for effecting a fore-and-aft adjustment of the sleeve within the housing to obtain the proper initial setting of the dressing device in operative position. 115

38. A slug dressing unit as set forth in claim 34, wherein means is provided for obtaining a rough initial fore-and-aft adjustment of the sleeve within the housing, and other means is provided for obtaining a finer adjustment of the sleeve. 120

39. In a typographical casting machine, the combination of a slug casting mold, a periodically rotatable disc carrying said mold, and a rotary face cutter arranged to trim the printing faces of slugs cast in said mold during the normal rotation of the disc, said cutter being disposed to cut crosswise of the slugs. 125

40. In a line casting machine, the combination of a mold carrying member, and a cooperative rotary power-driven finishing device mounted to act upon the type face of a slug in a mold carried by said member. 130

41. In a line casting machine, the combination of a mold carrying member, and a cooperative rotary power-driven finishing device to act upon the type face of a slug in a mold carried by said member, said member and device being relatively movable to cause the finishing device to traverse the length of the type face of the slug. 135

42. In a line casting machine, the combination of a movable member carrying a type slug casting mold, and a rotary power-driven dressing device mounted to act on the type face of a slug in the mold during the movement of said member. 140

43. In a line casting machine, the combination of a rotatable mold wheel carrying a type slug casting mold, and a rotary power-driven dressing device located opposite to the face of the mold wheel to act on the type face of a slug in the mold during rotation of the mold wheel. 145

20	44. In a typographical casting machine, the combination of means for casting printing slugs of slightly greater than a given height, and automatic rotary power-driven means for dressing the printing faces of the cast slugs to remove irregularities or high spots in the type characters and to reduce them to the given height.	means for normally holding said device in operative position, and means for rendering said device inoperative.	80
10	45. In a line casting machine, the combination of a rotatable mold wheel carrying a type slug casting mold, a dressing device located opposite to the face of the mold wheel to act on the type face of a slug in the mold during rotation of the mold wheel, and means for rendering said device inoperative.	47. In a line casting machine, the combination of a rotatable mold wheel carrying a type slug casting mold, a rotary power-driven dressing device located opposite to the face of the mold wheel to act on the type face of a slug in the mold during rotation of the mold wheel, and means for rendering said device inoperative.	85
15	46. In a line casting machine, the combination of a rotatable mold wheel carrying a type slug casting mold, a dressing device mounted relatively to the mold wheel to act on the type face of a slug in the mold during rotation of the mold wheel, and means for rendering said device inoperative.	48. In a line casting machine, the combination of a rotatable mold wheel carrying a type slug casting mold, a rotary power-driven dressing device mounted relatively to the mold wheel to act on the type face of a slug in the mold during rotation of the mold wheel, means for normally holding said device in operative position, and means for rendering said device inoperative.	90
